Primary Examiner — Katrina A Betton(74) *Attorney, Agent, or Firm* — LKGGlobal | Lorenz & Kopf, LLP(57) **CLAIM**

The ornamental design for a table for an aircraft interior, as shown and described.

DESCRIPTION

FIG. 1 is a front perspective view of the aircraft interior table showing our new design;

FIG. 2 is a bottom perspective view thereof;

FIG. 3 is a front view thereof;

FIG. 4 is a first side thereof;

FIG. 5 is a top view thereof;

FIG. 6 is a back view thereof;

FIG. 7 is a second side view thereof; and,

FIG. 8 is a bottom view thereof.

In the drawings, the broken lines depict portions of the article that form no part of the claimed design.
